UNITED STATES PATENT OFFICE.

FERDINAND W. KROGH, OF SAN FRANCISCO, CALIFORNIA.

BALANCED CENTRIFUGAL PUMP.

1,153,321.

Specification of Letters Patent. Patented Sept. 14, 1915.

Application filed July 12, 1911. Serial No. 638,120.

To all whom it may concern:

Be it known that I, FERDINAND W. KROGH, of San Francisco, California, have invented certain new and useful Improvements in 5 Balanced Centrifugal Pumps, whereof the following is a specification.

My invention relates to balanced centrifugal pumps and the object of which is to provide in that class of pump means whereby 10 the impellers therein are automatically held in axial alinement and to eliminate thrust bearings or the like therefore reducing the friction and vibration in operation.

With this purpose in view my invention 15 consists in the axial adjustment of the impellers which I accomplish by cushioning the same against equalizing cushioning chambers and further consists in other parts and their combinations as will be described 20 in detail hereinafter and pointed out in the claims at the end hereof.

In the accompanying two sheets of drawings which form a part of this application I 25 have illustrated my invention in what I consider its best form and in which:—

Figure 1, is a longitudinal section in elevation of a centrifugal pump having a double suction inlet and embodying my invention as it appears in practice and Fig. 2, 30 is also a similar section but showing a centrifugal pump having a single suction inlet and a modification of my invention applied thereon.

Similar characters of references denote 35 corresponding parts throughout the several views of the drawing.

Detailed description.—I will now describe the mechanism of the apparatus set forth in the above figures of the drawings, in which, 40 1 represents the base upon which the supported parts of a centrifugal pump constructed as hereinafter mentioned, are set up such as, the casing 2 and bearing 3 in which is mounted the driving shaft 4, carrying the 45 impeller 5 adjusted in the casing 2, and pulley 6 connected to the source of power for driving the shaft 4 and consequently the impeller 5 mounted thereon. The casing is provided with side flange surfaces 7 and 7' 50 to which flanges 8 and 8' provided at the outlet end of suction pipes 9 and 9' are secured by bolts 10 or otherwise and the suction pipes are also provided with outwardly 55 projecting bearings 11 and 12 for the shaft 4 which passes through the bearing 11 and extend into the bearing 12 thus supporting

the shaft centrally within the casing 2 and the suction pipes 9 and 9' thereby equalizing the space area of the suction pipes.

The outer end of bearing 12 in which the 60 shaft 4 extends is closed as at 13 to prevent leakage at that point, while the bearing 11 at the opposite end through which the shaft passes is provided with stuffing box 14 for the same purpose.

Within the surrounding outlet ends of suction pipes 9 and 9' are circular suction chambers 15 and 15' facing the necks 16 and 16' of the impeller 5 and are formed by inwardly projecting inner walls 17 and 17' 70 and outer projecting walls 18 and 18'.

The walls 17 and 17' project toward the necks of the impeller leaving however, annular spaces 19 and 19' between to establish outlet communication with the suction chambers 15 and 15' and the suction inlets 20 and 20' of the impeller.

The outer walls 18 and 18' project over the circumference of the necks 16 and 16' of the impeller, leaving therebetween passages 80 21 and 21' to establish permanent inlet communication between the pressure chambers 22 and 22' and the suction chambers 15 and 15'.

The necks 16 and 16' are provided with 85 wearing surfaces 23 and 23' having an L shaped form and removably secured in position by means of screws 24 and 24' or otherwise, and the chambers 15 and 15' are provided with flushing pipes 25 and 25' having 90 valves 26 and 26' as shown in Fig. 1, the purpose of which is to clean out the sand or any other foreign matter which may accumulate therein, while in operation.

In Fig. 2, I have illustrated a modification of chambers 15 and 15' which consists in making that part of my invention adjustable by means of screws 27 and 27' connected to flanges 8 and 8' and engaging the 95 chambers.

Other modifications or changes may be made without altering the scope of my invention, such, for instance chambers 15 and 15' may be made in the necks 16 and 16' of the impeller, in this case the operation and 105 result will be substantially the same, therefore, I do not desire to limit myself to the peculiar construction shown.

The mode of operation of my pump is as follows:—The impeller 5 being set in motion, a partial vacuum is created in the suction pipes 9 and 9' and the fluid drawn up

through the impeller in the direction shown by the arrows until a pressure is created between the impeller and the casing 2 and said pressure is continuous throughout the annular spaces between the impeller 5 and the casing 2 exerting an even pressure on both sides of the impeller and thus keeping same in perfect alinement within the casing. Should, however, the impeller shift toward 5 suction chamber 15, for instance that will partly close the annular space 19, and the fluid in the pressure chamber 22 entering into the suction chamber 15 through the circumferential passage, 21, between the neck, 16, of the impeller and the outer wall, 18, of chamber, 15, cause the chamber, 15, to become a pressure chamber and at the same time opening the annular space 19' on the opposite side of the impeller. The circumferential passage, 21', between the neck 16', of the impeller and the outer wall, 18', of chamber, 15', communicating the pressure chamber, 22', with the suction chamber, 15', being smaller than the annular space, 19', just mentioned, by reason of the shifting position of the impeller, allow the fluid from the pressure chamber, 22', to enter into the suction chamber, 15', and to pass out into the suction inlet, of, the impeller more rapidly, thus creating a vacuum in the chamber, 15', and thereby force the impeller to return back to its normal position and vice versa until the impeller is balanced.

Having thus described my invention, and 25 an embodiment of it, in the full, clear and exact terms required by law, and knowing that it comprises novel, useful and valuable improvements in the art to which it pertains,

I here state that I do not wish to be limited to the precise construction and arrangement 40 of the several parts, as herein set forth, as the same may be variously modified by a skilled mechanic without departing from the spirit of the invention.

What I claim and desire to secure by Letters Patent of the United States is the following, to wit:—

1. A centrifugal pump comprising a casing, an impeller in said casing having a double suction inlet, chambers in said casing 50 adjacent to said suction inlets provided with inlet and outlet passages and means for varying the length of said inlet passages and the space of said outlet passages.

2. In combination with the casing and the 55 impeller of a centrifugal pump, a suction inlet on each side of said impeller, removable suction chambers in the casing engaging the suction sides of the impeller and means for adjusting said chambers in position.

3. A centrifugal pump comprising a casing, an impeller in said casing provided with outward projecting necks on the sides thereof, central suction inlets in said necks, adjustable pressure chambers formed in the casing adjacent to said necks and connected to said suction inlets.

In testimony that I claim the foregoing I have hereto set my hand this 6th day of 70 July 1911, in the presence of witnesses.

FERDINAND W. KROGH.
